CHILD'S SLIPPER SHOE AND METHOD FOR
MAKING SAMELouis J. Golden, Highland Park, Ill., assignor to
B and B Shoe Company, Chicago, Ill., a cor-
poration of Illinois

Application May 11, 1936, Serial No. 79,082

9 Claims. (Cl. 12—146)

This invention relates to a new and improved child's slipper shoe and the method of making the same.

It is an object of this invention to provide a child's slipper shoe and the method of making the same which is simpler and more economic in point of labor and material consumed.

It is a further object of this invention to provide a child's slipper shoe and the method of 10 making the same which more accurately fits the contour of the foot.

It is an additional object of the present invention to provide a child's slipper shoe and the method of making the same in which the vamp portion 15 of the shoe is made of a two-piece pattern formed in such a manner as to give the appearance of a one-piece front.

It is a further object of this invention to provide a child's slipper shoe and method of making the same which has no protruding or lumpy 20 seams in the instep portion of the shoe.

It is likewise an object of this invention to provide a child's slipper shoe and the method of making the same which is of simple construction, warm, durable and easy for a small child 25 to put on.

Other objects and advantages of the present invention will appear more fully from the following detailed description, which, taken in connection with the accompanying drawing, will disclose to those skilled in the art the construction and operation of a preferred form of the present invention.

Referring to the drawing:

Fig. 1 is a perspective view of a preferred embodiment of the present invention;

Fig. 2 is a diagrammatic representation of the various pieces forming the upper member of the embodiment shown in Fig. 1, showing those pieces in line for assembly;

Fig. 3 is a pattern view of the main vamp member shown in Fig. 2;

Fig. 4 is a detail view of the toe of the embodiment shown in Fig. 1, with the vamp insert in place;

Fig. 5 is a perspective view of the trim-strip; and

Fig. 6 is a pattern view of the heel member of the upper shown in Figs. 1 and 2.

The embodiment shown in Fig. 1 comprises a sole 1 which has a padded heel portion 2 as is customary in flat sole house slippers of this general type. Attached to the sole member 1 is an upper 3 which comprises a front or vamp portion 4 and a back or heel portion 5. The front por-

tion 4 is formed according to the pattern as shown in Fig. 3. A toe split 6 is formed in this vamp portion. A V-shaped insert 7, as shown in Figs. 2 and 4, is cut out of a flat piece of similar leather, preferably in such a way that the grain matches up with the grain of the leather in the member 4. The split 6 in the member 4 is then spread to form a notch to accommodate the triangular insert 7, somewhat as shown in Fig. 2. As this split is spread, the vamp portion 4 begins to take on a rounded shape whereby to form the toe portion of the shoe. The triangular insert 7 is stitched in place by a zigzag stitch 8, as shown in Fig. 4. This makes possible the formation of a butt joint along the seam line, 15 whereby the seam will be entirely flat on the inside of the shoe. A trim-strip 10 is die cut out of a flat piece of leather in the shape as shown in Fig. 5. This trim-strip is formed with a centrally extending split 11. This trim-strip is then spread apart, somewhat as shown in Fig. 2, to 20 form a V-shaped member adapted to fit over the seam 8. After the triangular insert 7 is stitched in place in the vamp member 4, the trim-strip is placed over the seam line. This should be 25 somewhat wider than the width of the zigzag stitches so as to cover the stitches completely and hide the same. This trim-strip is then sewed in place by a double line of stitches 12 and 13, respectively, as shown in Fig. 1. As this operation is finished it will be found that the vamp or combined instep covering and toe covering portion of the slipper will have acquired shape. The heel member 5 is cut out of a flat piece of 30 leather according to the pattern shown in Fig. 6. The shoe is completed by sewing or otherwise attaching the finished vamp member 4 and the heel member 5 to the sole member 1. The front member is attached to the heel member only by a short line of bar stitching 14, as shown in Fig. 40. This line of bar stitching is preferably used on both sides of the shoe. The heel member and front member, respectively, are free and overlapping along the edges 15 and 16, respectively, as shown in Fig. 1. Suitable fastening means, such as snap fasteners 17 and 18, may be fixed adjacent the ankle line of the shoe to secure the front and back members, respectively, together at the top.

If it is desired to make a lined house shoe or slipper, a separate lining may be formed in a manner similar to that described above for the upper member, and then secured inside the shoe. It has been found preferable, however, to cement a suitable lining material onto the back of the 55

leather out of which the shoe is to be made, prior to stamping out the patterns. Thus the lining and upper member may be cut at one and the same time and the entire job of forming the shoe be completed with fewer operations.

It will be apparent that the present invention results in the formation of a child's house shoe which may be made in a very economical fashion. The patterns are such that an unusually small amount of waste need be suffered; the shoe may be formed without the expenditure of a great deal of effort or labor in lasting or forming the shoe; the number of stitching operations required is greatly simplified and cut down; and the shoe when finished has a smooth inside surface which is not rough or seamed and can not therefore hurt or annoy the child's foot when the shoe is in use. The shoe is furthermore easy to put on and take off so that even the smallest child may use the shoe without parental assistance. The shoe is of a type which fits the foot neatly and snugly, fits well up around the child's ankle, and keeps the foot warm in winter.

It is thought that the invention and numerous of its attendant advantages will be understood from the foregoing description and it is obvious that numerous changes may be made in the form, construction and arrangement of the several parts without departing from the spirit or scope of my invention, or sacrificing any of its attendant advantages, the form herein described being a preferred embodiment for the purpose of illustrating my invention.

Having thus described the invention what is claimed as new and desired to be secured by Letters Patent is as follows:

1. The method of forming a shoe upper comprising cutting a front member as a single piece from a flat sheet of material, splitting the front member longitudinally inwardly of its forward edge, spreading the edges of the split to form a V-shaped opening, forming a triangular insert member, and securing the triangular insert member across the opening of the front member by fastening said insert member adjacent the edges of said V-shaped opening whereby to give the unit a rounded shape suitable for enclosing the front portion of the foot.

2. The method of forming a shoe upper comprising cutting a front member as a single piece from a flat sheet of material, splitting the front member longitudinally inwardly of its forward edge, spreading the edges of the split to form a V-shaped opening, forming a triangular insert member, securing the triangular insert member in the opening of the front member in a flat abutting relationship, forming a heel-covering portion, securing the heel-covering portion to the front member, forming a V-shaped strip member, and securing the V-shaped strip member to the insert and the front member respectively.

3. A shoe having a heel-covering portion and a one-piece front member formed of a sheet of normally substantially flat material, said front member being notched from the forward edge thereof a predetermined distance, and an insert sewn into the notch to provide a unit of rounded shape suitable to fit the contour of the forward part of the foot.

4. A shoe having a heel-covering portion and a one-piece front member comprising the toe or vamp portion of the shoe and having a rounded shape suitable to fit the contour of the forward part of the foot, said front member being formed of a blank comprising a normally substantially flat sheet of material, said blank being notched from the forward edge thereof a predetermined distance longitudinally inwardly, and an insert sewn thereinto.

5. A shoe having a heel-covering portion and a one-piece front member comprising a blank formed of a sheet of normally substantially flat material, said front member being notched from the forward edge thereof a predetermined distance inwardly, and a triangular insert fastened across the notch to maintain the unit in a shape suitable for fitting the contour of the forward part of the foot.

6. A shoe having a heel-covering portion and a one-piece front member formed of a sheet of normally substantially flat material, said front member being notched from the forward edge thereof a predetermined distance, and an insert sewn into the notch to provide a unit of rounded shape suitable to fit the contour of the forward part of the foot, said front member terminating rearwardly in a pair of upwardly extending edges disposed on either side of the shoe, said front member being joined to the heel-covering portion along said edges.

7. A shoe having a heel-covering portion and a one-piece front member comprising a blank formed of a sheet of normally substantially flat material, said front member being notched from the forward edge thereof a predetermined distance inwardly, and a triangular insert fastened across the notch to maintain the unit in a shape suitable for fitting the contour of the forward part of the foot, said front member and said heel-covering portion being contiguous adjacent the edges and being joined together for a short distance adjacent each of the contiguous portions.

8. A shoe having a heel-covering portion and a one-piece front member formed of a sheet of normally substantially flat material, said front member being notched from the forward edge thereof a predetermined distance, and an insert sewn into the notch to provide a unit of rounded shape suitable to fit the contour of the forward part of the foot, said front member terminating rearwardly in a pair of upwardly extending edges disposed on either side of the shoe, said front member being joined to the heel-covering portion along the lower portions of said edges only, the upper contiguous portions of the adjacent edges being free of permanent attachment.

9. A shoe having a heel-covering portion and a one-piece front member, said front member being formed from a substantially flat piece of sheet material and being notched from the forward edge thereof a predetermined distance inwardly, a triangular insert sewn into the notch to provide a rounded shape suitable to fit the contour of the forward part of the foot, and a V-shaped member sewn over the seam formed between the insert and the front member to form a covering for the seam therebetween.
